UNITED STATES PATENT OFFICE.

SAMUEL J. GILLESPIE, OF TACOMA, WASHINGTON, ASSIGNOR TO JOHN A. SAUERMAN,
OF CHICAGO, ILLINOIS.

MATERIAL-HANDLING APPARATUS.

Application filed March 6, 1922. Serial No. 541,265.

To all whom it may concern:

Be it known that I, SAMUEL J. GILLESPIE, a citizen of the United States, residing at Tacoma, in the county of Pierce and State 5 of Washington, have invented a new and useful Improvement in Material-Handling Apparatus, of which the following is a specification.

My invention relates, more particularly, 10 to apparatus for use in excavating or grading work, where it is desired that material, such as earth, be removed from one location to another, though the invention is not limited to such use.

15 My primary purpose is to provide apparatus of the general character above stated which may be used not only for carrying material, in suspended condition, from one place to another, but also may be used for 20 dragging the material to the desired point of deposit; or in other words to provide an apparatus affording in a single structure, a bucket which may be moved into the material to fill it and by which the material may 25 be carried to the point of deposit, such structure involving a bottom plate; and a bottomless scraper structure which may be dragged over the material to be displaced and operating to move the material without 30 suspending it. Another object of my invention is to provide a simple, relatively inexpensive and positively operating apparatus involving the bucket and scraper features, and to eliminate the necessity of providing 35 separate buckets and scrapers; and other objects as will be manifest from the following description.

Referring to the accompanying drawings: Figure 1 is a view in elevation of a material 40 handling apparatus involving my invention, and showing one of the forms in which it may be embodied and one of the uses to which it may be placed. Figure 2 is a perspective view of the combined bucket and 45 scraper element of the apparatus this element being shown in the position it assumes when being used as a scraper. Figure 3 is a view like Fig. 2 and of the structure therein shown illustrating the structure in inverted position in which it operates as a 50 bucket. Figure 4 is an enlarged view of a portion of the apparatus shown in Fig. 1 showing the combined bucket and scraper so positioned as to cause it to operate as a 55 scraper; and Figure 5 a view of the struc-

ture shown in Fig. 4 illustrating the combined bucket and scraper positioned to cause it to operate as a bucket.

As a premise to the following description, it may be stated that as to the broader idea 60 of my invention, it relates to the combined bucket and scraper regardless of the particular means employed in connection therewith for operating it, the particular means shown for this purpose merely being by way 65 of example.

Generally stated, and in accordance with the preferred embodiment of my invention, the combined bucket and scraper device is 70 so formed that when in one position it will operate as a bucket which, in being dragged into the material to be displaced, will become charged with the material and which will permit of the carrying thereby of the material to the point of deposit; and when 75 inverted, will operate as a substantially bottomless scraper which, in being dragged against the material to be displaced, will receive a charge of the material and drag it over the material beneath it to the place 80 of deposit.

The illustrated construction of combined bucket and scraper referred to comprises opposed side walls 6 extending, preferably, 85 in substantially parallel relation, an end wall 7 shown as, and preferably, of curved shape connected at its extremities with the side walls 6, and a bottom portion 8 connected at its sides with the side walls 6 and at its rear edge with the forward edge 9 of 90 the curved end wall 7. The bottom portion 8 preferably extends almost the entire length of the side walls 6 and at its forward extremity presents teeth 10 as is usual in bucket structures for enhancing the digging 95 effect. The portion of the structure opposite that closed by the bottom portion 8 is open as shown more particularly in Fig. 3, the forward edge of the end wall 7, opposite the edge 9 of this end wall, being preferably 100 formed with forwardly extending teeth 11 shown as carried by a plate 12 connected with the end wall 7. The structure also comprises a bail 13, the arms 14 of which are pivotally connected at their ends, as 105 represented at 15, to the forward extremities of the side walls 6, adapting this bail to be swung on the side walls 6 to permit it to be positioned in an upwardly extending direction regardless of the position occupied 110

by the combined bucket and scraper structure. The forward extremities of the side walls 6 contain openings 16, 17 and 18 for attachment thereto of a hauling line, and 5 the rear end wall 7 is equipped with an eye 19 for the attachment thereto of an operating element as hereinafter described.

From the foregoing it will be readily understood that when the combined bucket 10 and scraper structure is positioned as shown in Fig. 2 it will serve as a substantially bottomless scraper operating, when dragged over the material to be displaced, to dig 15 into the material and become charged therewith, the material, in the movement of the structure over the material, piling up into the interior of the structure and against the portion 8, which, in this position of the structure is at the top of the latter, and 20 operating to lift the structure sufficiently to prevent further digging, the structure with its load, in the continued movement of the structure over the material, sliding over the latter, the load being released from the 25 scraper by dragging the latter in a reverse direction or by lifting the scraper. It will also be understood that when the combined bucket and scraper structure is inverted into the position shown in Fig. 3, it will serve, 30 when dragged into the material to be displaced, to engage the material and become charged therewith in the manner common with scraper buckets as commonly provided, the portion 8, in this position of the structure, being at the bottom of the structure and serving, in combination with the side walls and end of the structure, to retain therein the material charged into it as stated, adapting its load to be carried, in a suspended 35 condition of the combined bucket and scraper structure, if desired, to the point of deposit, the load to be discharged from the structure in accordance with common practice.

40 In the drawings I have shown my combined bucket and scraper structure as forming an element of material-moving apparatus of the same general character as that shown in U. S. Letters Patent No. 998,789, granted to P. Mayer, July 29, 1911, this apparatus involving a mast 20 supported at a point beyond the material to be displaced and the place of discharge thereof. The mast 20 connects at its upper end with one 45 end of a slack-line cable-way 21, the other, lower end of which is anchored at 22 in the ground beyond the point at which the material to be displaced is located. The slack-line cable has interposed therein tauting means 23 shown as formed of two pulleys 24 and 25, the cable 21 being connected with the pulley 24, and a tension cable 26 connected with these pulleys in accordance with common practice and leading to a windlass 50 27 by the operation of which latter the cable

21 may be slackened and made taut, at will, as desired.

The apparatus also comprises a carriage 28 formed of a frame 29 provided with peripherally grooved wheels 30 journaled 70 thereon and at the peripheries of which the carriage is supported on the cable 21 adapting the carriage to be moved along this cable, the frame 29 also being provided with grooved pulleys 31 and 32 journaled thereon. A cable 33 extends over the pulley 32 and connects at one end with a swivel 34 pivoted on a cross-pin 35 carried by the bail 13, and at its other end with a swivel 36 pivoted at 37 on the eye 19. A cable 38 80 connects at one end with the swivel 36, extends over the pulley 31 and over a pulley 39 journaled in a pull-block 40 and thence upwardly where it is connected with a roller-block 41 rollingly supported on the cable 21 and adapted to co-operate with a stop-block 42 rigidly connected with the cable 21. The apparatus also involves a hauling element shown as formed of a cable 43 connected at one end with the pull-block 40 and at its opposite end with a windlass 44, this cable extending over a pulley 45 secured to the mast 20; the pull-block 40; a cable 46 connected at its forward end with the pull-block 40; and branch cables 47 and 48, the latter being a bridle-cable, connected at their forward ends to the rear end of the cable 46 and at their rear ends with the swivel 34 and with clevises 49, respectively, located at opposite sides of the combined bucket and scraper and secured thereto at certain of the openings 16, 17 and 18 as hereinbefore referred to.

Assuming the combined bucket and scraper to be positioned to operate as a 105 scraper, as hereinbefore referred to (Figures 1, 2 and 4), the combined bucket and scraper is pulled over the material to be displaced, by winding up the cable 43 on the windlass 44, the cable 21 being slackened sufficiently to permit the combined bucket and scraper to engage the material to be displaced, and where necessary, or desirable, to supplement the weight of the combined bucket and scraper by the addition of further weight thereto, in order that it will dig into the material to the desired extent, the cable 21 may be slackened sufficiently to permit the carriage 28 to rest upon the portion 8 of the structure. Where the cable-way 21 is inclined as shown, the load is released from the combined bucket and scraper by tauting the cable 21, the combined bucket and scraper being returned to a position preliminary to again operating it to displace more material, by paying out the cable 43, the carriage and the structure supported thereby gravitating on the cable 21. It will, of course, be understood that if desired, means such as a cable (not shown) attached to the 110

rear end of the combined bucket and scraper, may be provided for dragging the latter to the desired position preliminary to the operation of again charging it with material.

Assuming that it is desired to operate the apparatus for the digging and carrying of material, the combined bucket and scraper would be inverted from the position shown 10 in Fig. 2 to the position shown in Fig. 3, the bail 13 would be swung thereon to extend upwardly as shown in Fig. 3, and the position of the clevises 49 would be changed from that shown in Fig. 4 wherein they extend 15 through the openings 16 to the position shown in Fig. 5 wherein they extend through the openings 18. The combined bucket and scraper is charged with a load of the material to be displaced by hauling on the line 20 43, the cable 21 being preliminarily slackened, if conditions require, and after the load is received the line 21 is tauted to lift the combined bucket and scraper clear of the material, and the carriage 28, with the parts 25 carried thereby, drawn upwardly on the cable 21 to dumping position. The block 42 is positioned adjacent the point at which dumping is to take place, and as soon as the roller-block 41 engages the block 42, the pull 30 on the cable 43 being continued, the cable 38 is caused to travel to the right in Fig. 5 at a greater speed than the cable 46, with the result of tilting the combined bucket and scraper in a direction to discharge its load, 35 the carriage 48 and the parts associated therewith, as stated, running down the cable-way 21 and the combined bucket and scraper automatically swinging to the position shown in Fig. 5, upon slackening the hauling 40 line 43.

It will be understood from the foregoing that the use of separate buckets and scrapers are not required to be provided, inasmuch as the one device is so constructed that it is 45 adapted to perform the functions of both of such devices, and an apparatus suitable for both purposes may be provided not only more economically than apparatus has hitherto been provided, but may be quickly 50 conditioned for performing the different kinds of work referred to.

While I have illustrated and described my invention as employed in a system involving a slack-line cable-way with co-operating 55 parts of a certain construction, I do not wish to be understood as intending to limit it thereto, as the invention may be employed, as regards the use of the bucket and scraper features, not only in other constructions involving a slack-line cable-way, but also with any other suitable supporting means, such, for example, as a boom arrangement, or a rigid track-way upon which the carriage, and the parts carried thereby, are supported 60 and movable; and as a scraper may be used

when no support is possible. In connection with the use of a rigid track-way it may be stated that, under some conditions, material to be displaced is so positioned that the apparatus may function as a scraper without 70 requiring the elevating of the scraper to fully discharge its load, in which case it will not be necessary to raise the combined bucket and scraper to discharge the load.

What I claim as new, and desire to secure 75 by Letters Patent, is:—

1. A combined self-filling bucket and substantially bottomless scraper comprising a body open at its lower side, with a plate extending across its top side, said plate having a digging portion at its forward end and said body presenting a digging portion at its lower side, whereby in one position of said body it operates as a substantially bottomless scraper and when inverted operates 80 as a self-filling bucket.

2. A combined self-filling bucket and substantially bottomless scraper comprising a hollow body presenting digging portions at its top and lower sides, one of said digging 85 portions being in advance of the other thereof, for the purpose set forth.

3. A combined self-filling bucket and substantially bottomless scraper comprising side walls spaced apart, an end wall of 90 curved shape in cross-section, with its concave surface at the inside of said structure, and a bottom portion opposing the opening at the opposite side of the structure, the forward edges of said end wall and bottom 100 portion presenting digging portions, whereby in one position of the structure it operates as a self-filling bucket and when inverted operates as a substantially bottomless scraper.

4. A material-handling structure comprising side-walls spaced apart, an end wall and a bottom portion, the forward edges of said end wall and bottom portion presenting digging portions, and the said parts being 110 so constructed and arranged that when the structure is in one position it operates as a bucket and when inverted it operates as a substantially bottomless scraper.

5. A combined self-filling bucket and substantially bottomless scraper comprising a body open at its lower side, with a plate extending across its top side, said plate having a digging portion at its forward end and said body presenting a digging portion at its lower side, whereby in one position of said body it operates as a substantially bottomless scraper and when inverted operates 115 as a self-filling bucket, said body being provided with a bail for attachment thereto of a supporting element constructed and arranged to be positioned to extend upwardly in the different positions of said body.

6. A combined self-filling bucket and substantially bottomless scraper comprising a 120

body open at its lower side, with a plate extending across its top side, said plate having a digging portion at its forward end and said body presenting a digging portion at its lower side, whereby in one position of said body it operates as a substantially bottomless scraper and when inverted operates as a self-filling bucket, said body having a bail pivoted thereon for attachment 10 of the bail to a supporting element, for the purpose set forth.

7. In combination with a supporting structure a combined self-filling bucket and substantially bottomless scraper supported 15 thereon and comprising a body open at its lower side, with a plate extending across its top side, said plate having a digging portion at its forward end and said body presenting a digging portion at its lower side, 20 whereby in one position of said body it operates as a substantially bottomless scraper and when inverted operates as a self-filling bucket.

8. A combined self-filling bucket and substantially bottomless scraper comprising a body open at its lower side, with a plate extending across its top side, said plate having a digging portion at its forward end and said body presenting a digging portion at 25 its lower side, whereby in one position of said body it operates as a substantially bottomless scraper, and when inverted operates as a self-filling bucket, said body being provided with a body-supporting bail adapted 30 to be swung on said body across the front end of the latter to extend upwardly in either position of said body, and a supporting structure for said body comprising connections with said body at said bail at one 35 end and with the rear end of said body, adapting the latter to be turned over sideways without disturbing said connections.

9. A combined self-filling bucket and substantially bottomless scraper comprising a body open at its lower side, with a plate extending across its top side, said plate having a digging portion at its forward end and said body presenting a digging portion at its lower side, whereby in one position of said body it operates as a substantially bottomless scraper and when inverted operates as a self-filling bucket, said body being provided with a body-supporting bail adapted 45 to be swung on said body across the front end of the latter to extend upwardly in either position of said body, and a supporting structure for said body comprising connections with said body at said bail at one 50 end and with the rear end of said body, said connections involving swivels adapting said body to be turned over sideways without disturbing said connections.

10. A combined self-filling bucket and substantially bottomless scraper comprising a body open at its lower side, with a plate 55 extending across its top side, said plate having a digging portion at its forward end and said body presenting a digging portion at its lower side, whereby in one position of said body it operates as a substantially bottomless scraper, and when inverted operates as a self-filling bucket, said body being provided with a body-supporting bail adapted 60 to be swung on said body across the front end of the latter to extend upwardly in either position of said body, and a supporting structure for said body comprising 65 flexible elements connected with said body at said bail at one end and with the rear end of said body, adapting said body to be 70 turned over sideways without disturbing the connections between said elements and said supporting structure and body.

SAMUEL J. GILLESPIE.
